(57) **CLAIM**

The ornamental design for a key button arrangement for a handset, as shown and described.

DESCRIPTION

FIG. 1 is a front view of a key button arrangement for a handset showing my new design; and,

FIG. 2 is a perspective front view thereof.

The uneven broken line showing of the remainder of the handset and keypad is for illustrative purposes only and forms no part of the claimed design.

1 Claim, 2 Drawing Sheets

FIG. 1

FIG. 2
